Attorney

UNITED STATES PATENT OFFICE.

CORA CUNNINGHAM, OF MARLINTON, WEST VIRGINIA.

CLOTHESPIN BAG.

Application filed July 14, 1928. Serial No. 292,782.

This invention relates to the class of cloth receptacles and pertains particularly to a bag designed primarily for the reception of clothes pins or other small articles.

5 One of the primary objects of the invention is to provide, in a manner as hereinafter set forth, a fabric receptacle having a hingedly attached cover and including novel means for suspending the receptacle by the 10 cover or by the body of the bag.

A further object of the invention is to provide, in a manner as hereinafter set forth, a receptacle having a hingedly attached cover, including a novel means for 15 securing the cover in closed position.

Other objects and advantages of the present invention will become apparent as the description of the same proceeds and the invention will be best understood from a consideration of the following detailed description taken in connection with the accompanying drawings forming part of this specification, with the understanding, however, that the invention is not confined to 25 any strict conformity with the showing of the drawings but may be changed or modified so long as such changes or modifications mark no material departure from the salient features of the invention as expressed in the 30 appended claims.

In the drawing:—

Figure 1 is a rear elevational view of the bag embodying the present invention, showing the top raised;

35 Figure 2 is a transverse section taken upon the line 2—2 of Figure 1;

Figure 3 is a detailed perspective view of one corner connection between the bag top frame and the cover frame;

40 Figure 4 is a detailed plan view of the hanging loop forming a part of the bag top frame.

Referring more particularly to the drawing, wherein similar reference characters indicate like parts throughout the several views, the numeral 1 indicates generally the body of the bag comprising the present invention, the top thereof being indicated generally by the numeral 2.

50 The bag structure 1 comprises a substantially U-shaped frame 3 which constitutes a form for the mouth thereof, which frame comprises the elongated front or yoke portion 4 and integral side leg portions 5, the 55 free end of each of which legs is formed to provide an eye 6 which has hinge connection

with the frame 7 of the top 2 in the manner hereinafter described. The frames 3 and 7 may be formed of any suitable material such as heavy wire or the like and the central portion 4 of the frame 3 is bent to provide a hanging loop 8 by means of which the back may be suspended from a hook or nail support.

50 The frame 7 of the top 2 is also of substantially U-shaped configuration, being made up of the yoke portion 9 and the side legs 10. However, the ends of the legs 10 are joined by a bail 11 which extends inwardly over the upper surface of the top, 60 the curved portion 12, lying between the ends of the bail and the adjoining legs 10 of the top frame, being designed to engage over a supporting line, such for example as a clothes line, to maintain the bag in position thereon.

65 The legs 10 of the top frame, adjacent their point of joinder with the yoke portion 9 of this yoke frame, which yoke forms the back bar of the mouth of the completed bag, are bent to provide inwardly projecting elongated loops 13, the sides 14 of which are straight and substantially parallel.

70 The loops 13 are not in the same plane as the side members or legs 10 of the frame but project at a slight angle forwardly, thus also positioning the yoke bar 9 forwardly of the frame as shown in Figure 3. The upper portion 14 of each of the loops 13 extends through an eye 6 of a leg of the bag 80 top frame 3 and, as is clearly shown, the cover frame is thus permitted to swing relative to the bag top frame and when the bag is open, each of the legs 5 of the bag top frame will rest upon the portion 14 of 90 a loop adjacent the portion to which it is attached.

95 A suitable fabric bag 15 is provided, the edge of the mouth of which is formed to provide a surrounding hem 16 through 100 which at three sides of the bag, the portions 4 and 5 of the frame 3 pass, suitable openings being made at the back of the bag to permit the ends of the legs 5 to project therefrom. An opening is also provided at the front 105 edge to permit the extension from the hem of the loop 8.

110 The yoke bar 9 of the cover frame 7 extends through the hem at the rear edge of the bag and a cover fabric 16 is placed over the cover frame, this fabric being provided with the hems 17 along each side edge for

the reception of the portions 10 of the cover frame, the inner edge thereof being secured to the rear edge of the bag 15 or, to the hem through which the portion 9 of the cover frame passes.

5 The front edge of the cover fabric 16 connects the forward ends of the cover frame portions or legs 7 and intermediate the ends of this free edge, there is secured an elastic 10 18, this elastic being attached at its ends as indicated at 19, while in a stretched condition, thus acting when released to draw the sides of the cover fabric together and also to draw the leg portions 10 of the cover 15 frame inwardly.

When the bag is in use, it may be suspended, as above described, from a clothes line or similar support by engaging the bail 11, which overlies the upper surface of the 20 top, thereover under which conditions the bag will naturally drop to open position. When it is desired to close the bag, the frame 3 is swung upwardly and the leg members 10 of the cover frame are spread apart 25 against the tension of the elastic 18 to permit the bag frame to pass beyond the cover frame legs, after which the cover frame legs are released and the elastic acts to draw them inwardly so that they will engage under the legs 5 of the bag top frame and hold the bag in closed position.

It is, of course, obvious that a snap catch or fastener may be employed for maintaining the frames in juxtaposition where it 35 may be desirable to provide holding means which can be operated without the use of both hands.

From the foregoing description, it will be readily seen that the herein described bag 40 may be advantageously employed in many capacities other than for the storage of clothes pins, as for example, it will be found of great convenience on motor trips where it may be used for carrying soap, wash 45 cloths, and toilet articles.

Having described my invention, what I claim is:—

1. A receptacle of the character described, comprising a body structure having a stiffening frame about the mouth of the body structure, a cover, a flexible frame for said cover open at one side, and flexible means extending across said open side of said last mentioned frame permitting the flexible frame to be spread for engagement over the stiffening frame to maintain the cover in closed position.

2. A receptacle of the character described comprising an open body, a substantially 60 U-shaped frame reinforcing the mouth of said body, a cover of flexible material, a reinforcing frame for said cover, hinge connecting means between the free ends of the legs of said U-shaped frame and said cover frame, and means forming a part of said

hinge means for engaging said legs when the cover is in open position to limit its movement with respect to the mouth of the receptacle.

3. In a receptacle of the character described, 70 an open bag, a substantially U-shaped frame attached to and reinforcing the mouth of the bag, a substantially U-shaped cover frame, means for setting up hinged connection between the ends of the 75 legs of the first-mentioned frame with the inner ends of the legs of the cover frame, a covering material for the cover frame, and resilient means normally acting upon the legs of the cover frame to draw the same 80 together, said cover frame legs being constructed to be spread against the action of the resilient means to permit the extension of the bag reinforcing frame therebetween.

4. In a receptacle of the character described, 85 an open bag, a substantially U-shaped frame attached to and reinforcing the mouth of the bag, a substantially U-shaped cover frame, means for setting up hinged connection between the ends of the 90 legs of the first-mentioned frame with the inner ends of the legs of the cover frame, a covering material for the cover frame, resilient means normally acting upon the legs of the cover frame to draw the same 95 together, said cover frame legs being constructed to be spread against the action of the resilient means to permit the extension of the bag reinforcing frame therebetween, and a supporting bail connecting the ends 100 of the cover frame legs and providing means for attaching the same to a support.

5. In a receptacle of the character described, 105 a flexible bag body, a substantially U-shaped reinforcing frame attached to the edge of the body at the mouth thereof, each of the legs of said frame terminating in an eye, a fabric cover, a substantially U-shaped reinforcing frame for said cover having the yoke portion attached to that edge of the 110 mouth of the bag lying between the free ends of the first-mentioned frame, an elongated inwardly extending loop formed at the inner end of each leg of the cover frame adjacent the point of joinder of the same 115 with said yoke, one side of each of said loops being extended through one of said eyes to set up a hinge connection between the frames, and means for securing the frames together to maintain the cover frame 120 in closed position over the mouth of the bag.

6. In a receptacle of the character described, 125 a flexible bag body, a substantially U-shaped reinforcing frame attached to the edge of the body at the mouth thereof, each of the legs of said frame terminating in an eye, a fabric cover, a substantially U-shaped reinforcing frame for said cover having the yoke portion attached to that edge of the 130

mouth of the bag lying between the free ends of the first-mentioned frame, an elongated inwardly extending loop formed at the inner end of each leg of the cover frame 5 adjacent the point of joinder of the same with said yoke, one side of each of said loops being extended through one of said eyes to set up a hinge connection between the frames, a supporting bail connecting the 10 free ends of the legs of the cover frame and positioned to overlie the outer surface of the cover, and means for coupling said cover frame with the other frame to maintain the cover in closed position.

15 7. In a receptacle of the character described, a flexible bag body, a substantially U-shaped reinforcing frame attached to the edge of the body at the mouth thereof, each of the legs of said frame terminating in an eye, a fabric cover, a substantially U-shaped reinforcing frame for said cover having the yoke portion attached to that edge of the 20 mouth of the bag lying between the free ends of the first-mentioned frame, an elongated inwardly extending loop formed at the inner end of each leg of the cover frame adjacent the point of joinder of the same with said yoke, one side of each of said loops being extended through one of said eyes to set up a hinge connection between the frames, and means for securing the frames together to maintain the cover frame in 25 closed position over the mouth of the bag, the other side of each of said loops being offset with respect to the eye engaging side to set up a stop for the adjacent eye carrying leg, to limit the opening movement of the 30 cover with respect to the bag mouth.

35 In testimony whereof I hereunto affix my signature.

CORA CUNNINGHAM.

In testimony whereof I hereunto affix my signature.
